UNITED STATES PATENT OFFICE.

JULIUS ROEMER, OF LAKEWOOD, OHIO.

HUMIDIFIER.

Application filed March 21, 1927. Serial No. 176,916.

My invention relates to air moistening devices, and particularly to providing an evaporator for liquids, in which by reason of having a relatively small quantity of liquid spread over a relatively large area the rate of evaporation will be greatly accelerated, and also to provide an evaporator in which a sudden inflow of liquid from a source of supply will be collected in the evaporator and carried away, thereby preventing an overflow of liquid onto the walls of a furnace with which the evaporator is used, or into a compartment in which the evaporator may be installed, and the principal object of my invention is to provide a new and improved evaporator of this type. In the drawings accompanying this specification and forming a part of this application I have shown, for purposes of illustration, various forms which my invention may assume, and in these drawings:

Figure 1 is a section showing one embodiment of my invention assembled with a radiator,

Figure 2 is a vertical section on an enlarged scale of the evaporator shown in Figure 1,

Figure 3 is a similar view showing an auxiliary heating means,

Figure 4 is a plan view of the auxiliary heating means of Figure 3,

Figure 5 is a vertical section of an evaporator adapted for use with a furnace, while

Figures 6, 7, and 8 are similar views of variant forms.

The embodiment of my invention disclosed in Figures 1 to 3 inclusive comprises a metallic structure 11 having a chamber 12 enclosed by a cylindrical side wall 13, a bottom wall 14, and a centrally depressed top wall 15, and adapted to be installed in the floor 16 adjacent a radiator 17 beneath which is a register 18 through which the products of evaporation are adapted to pass.

The structure 11 is designed to be heated by steam introduced into the chamber 12 through a conduit 19 having a connection with the steam pipe 20 of a heating system, and the water resulting from the condensation of such steam is carried away by a return pipe 21. A valve 22 is provided for relieving the air within the chamber 12.

The centrally depressed top portion 15 has a tapered side wall 23 which is provided with a series of substantially V-shaped troughs 24

arranged in parallel relation one above the other and each having a relatively wide upper wall 25 disposed at a relatively small angle to the horizontal plane and a lower relatively narrow wall 26 disposed at a relatively right angle to the horizontal plane. A pipe 27 connected with a suitable source of liquid supply, having means for either manually or automatically controlling the flow of liquid, is provided for introducing the necessary liquid into the top trough 24 from which it spills over the edge into the next trough 24 which when filled in turn spills into the adjacent trough 24 and so on to the lowermost trough 24 of the depression 60 70 which is cup-shaped to collect any excess liquid from the higher troughs 24 and is provided with a drain pipe 28 to carry away such excess liquids, thus preventing any overflowing from the accumulation of excess liquid 75 in the evaporator 11. By thus providing an evaporator in which a thin layer of liquid is spread over a relatively large heated area the rate of evaporation is greatly accelerated.

Where the device is applied to a vacuum 80 heating system the temperature of the vapor of the system may be insufficient to provide a rate of evaporation to properly humidify the atmosphere. Accordingly, I provide the auxiliary heating means shown in Figures 3 85 and 4 and consisting of an electric heating element 29 designed to be used with an alternating current and consisting of a pair of intercoiled copper plates 30 and 31 retained in spaced apart relation by a plate 32 of insulating material. This device is adapted to be disposed in the centrally depressed portion 15 adjacent to, but spaced away from the bottom thereof, so that when the accumulated liquid reaches a pre-determined 90 depth the water acts to establish a circuit between the intercoiled plates 30 and 31 thus causing a boiling of liquid which continues until the liquid has accumulated to a second pre-determined depth whereupon the depression 95 is emptied by a siphon drain pipe 33 and the heating action of the element ceases until such time as the accumulated liquid again establishes a circuit between the two plates 30 and 31. 100

The embodiment of my invention shown in Figure 5 is designed to be disposed upon the top of a heating furnace and consists of a frusto-conical metallic structure 35 having a centrally depressed top portion 36 and a 110

drain pipe 37 for carrying away excess liquid which accumulates in the lowermost portion of the depression.

The form shown in Figure 6 is designed 5 likewise to be disposed on the top of a furnace of a heating system and is adapted to be adjusted to furnaces having tops of different contour so that the depressed liquid containing portion may be brought into contact with 10 the top of the furnace irrespective of its shape and consists of a frusto-conical base member 40 having an outer shell member 41 of greater width than the base member 40 overlying the base member 40 and a liquid 15 receiving bowl portion 42 provided with troughs in its side wall 43 and adjustable upon the base 40 by means of set screws 44 adjustable in slots 45 in the outer shell member 41.

20 In the variation shown in Figure 7 the bottom wall is omitted and diametrically opposed portions of the side wall 13 are connected by a cross bar 46 which supports a gas burner 47 that supplies the heat of evaporation for the liquid contained in the bowl portion 48 and is provided with a flue 49 for carrying off the products of combustion.

The variation shown in Figure 8 comprises 30 a similar device having the bottom wall 50 formed of a pad of asbestos upon which is disposed an electric heating element 51 which supplies the necessary heat for evaporating the liquid in the bowl 48.

35 From the above disclosure it will be obvious to those skilled in the art that I have provided a new and improved evaporator adapted to be used with heating systems for moistening the air and having a construction such that the rate of evaporation of any liquid supplied thereto is greatly accelerated and is so arranged that any sudden inflow of liquid from a source of supply will be collected in the evaporator and carried away, thereby preventing an overflow of such liquid onto the 40 walls of a furnace or into a compartment in the wall of a building in which the evaporator may be disposed.

It will therefore be apparent to those skilled in the art that the embodiment of my 50 invention herein shown and described accomplishes at least the principal object of my invention.

At the same time it also will be obvious to those skilled in the art that the embodiment of my invention herein shown and described may be variously changed and modified without departing from the spirit of my invention or sacrificing the advantages thereof, and it therefore will be understood that the disclosure herein is illustrative only, and that my invention is not limited thereto.

I claim:

1. An evaporator for use in connection with 65 a heating system comprising: a metallic structure adapted to be heated and having a cen-

trally depressed top portion in the shape of a bowl having its side walls comprising a series of liquid receiving troughs so arranged that liquid introduced in said bowl flows downwardly over the heated surfaces of said troughs until evaporated.

2. An evaporator for use in connection with a heating system comprising: a metallic structure adapted to be heated and having a centrally depressed top portion in the shape of a bowl having its side walls comprising a series of liquid receiving troughs disposed one above the other, and means for supplying liquid at a point near the edge of said bowl whence it may flow downwardly over 75 the heated surfaces of said troughs until evaporated.

3. An evaporator for use in connection with a heating system comprising: a metallic structure adapted to be heated and having a centrally depressed top portion in the shape of a bowl having its side walls comprising a series of liquid receiving troughs disposed parallel to each other one above the other, whereby liquid introduced in said bowl flows downwardly over the heated surfaces of said troughs until evaporated.

4. An evaporator for use in connection with a heating system comprising: a metallic structure adapted to be heated and having a centrally depressed top portion in the shape of a bowl having its side walls comprising a series of substantially V-shaped liquid receiving troughs one above the other and each having its upper side disposed at a relatively small angle to the horizontal plane, and its lower side disposed at a relatively great angle to the horizontal plane, whereby a relatively large heated surface is presented to the liquid flowing downwardly over said troughs.

5. An evaporator for use in connection with a heating system comprising: a metallic structure adapted to be heated and having a centrally depressed top portion in the shape of a bowl having its side walls comprising a series of liquid receiving troughs so arranged that liquid introduced into said bowl flows downwardly over the heated surfaces of said troughs, and a drain pipe communicating with the lowermost portion of said bowl for carrying away excess liquid.

6. An evaporator for use in connection with a heating system comprising: a base adapted to be disposed upon a furnace, a metallic structure adapted to be heated and adjustable on said base and having a centrally depressed top portion in the shape of a bowl having its side walls comprising a series of substantially V-shaped liquid receiving troughs disposed parallel to each other one above the other and each trough having its upper side disposed at a relatively small angle to the horizontal plane, and its lower side disposed at a relatively great angle to the horizontal plane, whereby a relatively large heat-

ed surface is presented to the liquid flowing downwardly over said troughs, and a drain pipe communicating with the lowermost portion of said bowl for carrying away excess liquid.

7. An evaporator for use in connection with a heating system comprising: a base, a metallic structure adapted to be heated and adjustable on said base and having a centrally depressed top portion in the shape of a bowl having its side walls comprising a series of liquid receiving troughs so arranged that liquid introduced into said bowl flows downwardly over a relatively large heated surface of said troughs until evaporated.

8. An evaporator for use in connection with a heating system comprising: a base, a metallic structure adapted to be heated and adjustable on said base and having a centrally depressed top portion in the shape of a bowl having its side walls comprising a series of substantially V-shaped liquid receiving troughs disposed parallel to each other one above the other and each trough having its upper side disposed at a relatively small angle to the horizontal plane, and its lower side disposed at a relatively great angle to the horizontal plane, whereby a relatively large heated surface is presented to the liquid flowing downwardly over said troughs.

9. An evaporator for use in connection with a heating system comprising: a metallic structure adapted to be disposed upon a furnace and having a centrally depressed top portion in the shape of a bowl having its side walls comprising a series of liquid receiving troughs so arranged that liquid introduced into said bowl flows downwardly over a relatively large heated surface of the troughs until evaporated.

10. An evaporator for use in connection with a heating system comprising: a casing forming a chamber and having a centrally depressed top portion in the shape of a bowl having its sides comprising a series of liquid receiving troughs, and means for introducing steam in said chamber for evaporating liquid contained in said troughs.

11. An evaporator for use in connection with a heating system comprising: a casing forming a chamber and having a centrally depressed top portion in the shape of a bowl having its sides comprising a series of liquid receiving troughs, means for introducing steam in said chamber for evaporating liquid contained in said troughs, and auxiliary heating means for heating said liquid comprising an electrically energized heating element disposed in the lower portion of said depressed top portion and brought into action when the accumulated liquid in said depressed top portion reaches a predetermined depth and siphon means for draining away

the accumulated liquid when it has reached another predetermined depth.

12. An evaporator for use in connection with a heating system comprising: a casing forming a chamber and having a centrally depressed top portion in the shape of a bowl having its sides comprising a series of liquid receiving troughs one above the other, means for introducing steam in said chamber for evaporating said liquid, and auxiliary heating means for heating said liquid comprising an electrically energized heating element disposed in the lower portion of said depression and brought into action when the accumulated liquid in said depression reaches a predetermined depth and siphon means for draining away the accumulated liquid when it has reached another predetermined depth.

13. In a steam heating system, a humidifying apparatus comprising, a casing forming a chamber and having a centrally depressed top portion in the shape of a bowl having its sides channeled to form a series of horizontal liquid-receiving troughs arranged in overflowing relation one above the other, means for introducing steam into said chamber, and means for delivering water into one of the uppermost troughs.

14. In a steam heating system, the combination with a floor type steam radiator of a hollow casing supported below said floor, adjacent to said radiator, the floor having an opening therein below said radiator and adjacent to said casing, and said casing being hollow, forming a chamber for the reception of steam, the top of said casing having a centrally depressed portion in the shape of a bowl, the sides of which comprise a series of liquid-receiving troughs, steam connections between the interior of said chamber and the supply pipes of said radiator, and means for supplying liquid to be evaporated to one of said troughs.

15. In a steam heating system, the combination with a floor type steam radiator of a hollow casing supported below said floor, adjacent to said radiator, the floor having an opening therein below said radiator and adjacent to said casing, and said casing being hollow, forming a chamber for the reception of steam, the top of said casing having a centrally depressed portion in the shape of a bowl, the sides of which comprise a series of liquid-receiving troughs, steam connections between the interior of said chamber and the supply pipes of said radiator, and means for supplying liquid to be evaporated to one of said troughs, and a drain pipe for removing any unevaporated accumulation of liquid from the bottom of such bowl.

In testimony whereof I hereunto affix my signature.

JULIUS ROEMER.
